UNITED STATES PATENT OFFICE

2,606,365

HAIR THINNING SCISSORS

Vincent R. Pileggi, Philadelphia, Pa.

Application May 22, 1950, Serial No. 163,507

2 Claims. (Cl. 30—195)

1

My invention relates to scissors and relates particularly to an improvement in scissors for cutting and thinning hair whereby even a novice may achieve unusual results.

Heretofore, various methods have been utilized to cut and thin very thick hair but they all require a high degree of skill and considerable expenditure of time. My improved invention may be used by anyone to cut and thin the hair, as well as to cut waves in the hair.

It, therefore, is an object of my invention to provide a hair thinning scissors whose use does not require any special skills.

Another object of my invention is to provide a hair thinning scissors to accomplish the hair thinning operation with a considerable saving in time.

Another object of my invention is to provide a scissors which will enable anyone to cut waves in the hair.

Other objects of my invention are to provide an improved hair cutting and thinning scissors, which are simple and sturdy in construction, economical to produce, and highly efficient in operation.

With the above and related objects in view, my invention consists in the details of construction and combination of parts, as will be more fully understood when the following description is read in conjunction with the accompanying drawing in which:

Fig. 1 is a top plan view of my invention.

Fig. 2 is a side plan view of my invention.

Fig. 3 is a cut-away view illustrating the manner in which my invention is used.

Fig. 4 is a cut-away perspective view showing the action of my scissors on the hair.

Referring now in greater detail to the drawing wherein similar reference characters denote like parts, I show a pair of hair thinning scissors, generally designated as A, having a cutting blade adapted to thin hair, generally designated as B, and a regular scissor blade, generally designated as C.

The scissors A comprises the blades B and C, the screw 50 holds the blades B and C face to face.

The hair thinning blade B is provided with a series of grooves 10, 12, 14, 16, 18, 20, 22 and 24 across the full width of the blade B, breaking up the cutting portion of the blade B into cutting sections 26, 28, 30, 32, 34, 36, 38, 40 and 42. The grooves 10, 12, 14 etc. are made to accommodate strands of hair which are not to be cut, the grooves gradually decreasing in size so that more

hair is cut toward the fulcrum of the pivoted blades B and C than at their free ends. The cutting sections 26, 28, 30 etc. are approximately equal in length.

5 The blade C is an ordinary barber's scissors blade having a continuous cutting edge 44.

The blades B and C are held face to face by a screw 50, or any other suitable means, which acts as a fulcrum between the blades B and C and the 10 handles 52.

The hair 46 to be thinned is combed so that it is held extended from the head and the scissors A is passed therethrough cutting away excess hair in the manner illustrated in Fig. 3. As is 15 readily seen, a greater amount of hair is left on the outside, enabling the thinned portions to be readily covered. To clarify this thinning action further, Fig. 4 shows the action of one cutting section 32 on a strand of hair 48. The strand of 20 hair is taken between the blades B and C with the hair filling the groove 16 with the excess hair flowing over the cutting section 32 of the blade B. When the blades B and C are brought together the cutting section 32 and the cutting 25 portion 44 of the blade C interact to shear off the excess hair, leaving the portion of the strand of hair in the groove 16 intact.

Waves may be easily cut in the hair 46 with my 30 improved scissors by thinning the hair 46 over a chartered course of predetermined spots or areas so that when the hair is combed, the longer strands lay over the thinned areas as well as the unthinned areas in between, a waved effect is achieved.

35 The tip ends of the blades are suitable for cutting and the intermediate portion of the blades are suitable for thinning the hair. Hence, with 40 my invention a single pair of scissors can be used for cutting the hair and thinning the hair. (See my previous filed patent application filed November 29, 1949, Serial No. 129,958, now abandoned.)

45 Although my invention has been described in considerable detail, such description is intended as merely illustrative rather than limiting, as my invention may be variously embodied, and the scope of the invention is to be determined as claimed.

I claim as my invention:

50 1. A hair thinning scissors comprising a first cutting blade having its cutting portion broken by a series of grooves across the width of the blade; a second cutting blade with a continuous cutting portion; said cutting portions interacting to shear hair, a first handle at one end of said first blade; a second handle at one end of said

second blade; and attaching means positioned between said handles and said cutting portions to pivot said blades face to face, said grooves gradually decreasing in width so that more hair is cut toward said attaching means of the pivoted blades than at their free ends.

2. A hair thinning scissors comprising a first cutting blade having its cutting portion broken by a series of grooves across the width of the blade; a second cutting blade with a continuous cutting portion; said cutting portions interacting to shear hair, a first handle at one end of said first blade; a second handle at one end of said second blade; and attaching means positioned between said handles and said cutting portions

15

to pivot said blades face to face, said grooves gradually decreasing in width so that more hair is cut toward said attaching means of the pivoted blades than at their free ends, and the cutting edges between the grooves being of approximately equal length.

VINCENT R. PILEGGI.
